SAFETY HAT OR THE LIKE

Harry W. Austin, Monroeville, Pa., assignor to Mine
Safety Appliances Company

Application April 12, 1956, Serial No. 41,039

Term of patent 14 years

(Cl. D3—13)

Fig. 1 is a front elevational view of a safety hat or the like, showing my new design;

Fig. 2 is a rear elevational view thereof;

Fig. 3 is a top plan view thereof;

Fig. 4 is a side elevational view thereof; and

Fig. 5 is a bottom perspective view thereof, showing the interior of the safety hat or the like.

I claim:

The ornamental design for a safety hat or the like, as shown.
